his Atty.

UNITED STATES PATENT OFFICE

MARSHALL D. GIBSON, OF WEBSTER GROVES, MISSOURI

CAN OPENER

Application filed February 14, 1927. Serial No. 168,048.

This invention relates to can openers. It has for its objects to produce a simple and efficient tool which will cut out the head of a can close up to the annular marginal portion thereof neatly and with a relatively clean cut so as to leave no dangerously jagged edge; to produce a device which may be manipulated either in a right or left handed manner; to minimize the cost of manufacture; and to attain certain advantages as will hereinafter more fully appear.

The invention consists in a novel arrangement of bifurcated cutter comprising a co-operating pair of double-edged cutting blades one of which functions as a guide while the other is operating as a cutter and either blade being thus operable at will. It further consists in the peculiar form and arrangement of the associated parts cooperating with said blades and in the general structure in the combinations and arrangements as hereinafter specified and afterwards pointed out with particularity in the appended claims.

In the accompanying drawings illustrating practical adaptations of the invention,—

Figure 1 is a side view of one construction of the tool;

Figure 2 is a similar view taken at right angles to that shown in Figure 1;

Figure 3 is a face view of one of the cutting blades and cooperating spacing member having the shank portion to which the operating handle is attachable;

Figure 4 is an edge view of the two cutting blades, spacing member and rivets detached to show the details thereof;

Figure 5 is a side view of a modified structure; and

Figure 6 is a similar view of said modification taken at right angles to that shown in Figure 5.

Referring now more particularly to Figures 1 to 4, inclusive, of the drawings, the numeral 1 designates the handle member of the tool which may be of any desirable form and of any suitable material. That shown indicates a plain wooden handle having the usual ferrule 2 at its end in which is inserted the tapered shank portion 3 of a filler or spac-

ing member 4, which letter, as shown, is of rectangular, flat, plate-like body.

The member 4 is composed of relatively hard metal or a metal which is specially tempered or casehardened so as to prevent wearing away of the sharp forward corners 5 thereof which have a special function as will presently more fully appear.

Secured on opposite sides of the member 4 are the rectangular base portions 6 of the cutting blades 7 which are rigidly held in place by rivets 8 or by other suitable means. The base portions 6 are wider and longer than the body portion of the filler or spacing member 4 so that the forward and side marginal portions of the former overhang the corresponding marginal portions of the latter and thereby produce channels 9, 10, respectively (see Figures 1, 2 and 3 of the drawings). The thickness of the member 4 is such that the channels 9, 10, are of a width between walls so as to straddle the usual annular marginal bead which is formed in heading the average regular cans.

The cutting blade portions proper 7 are 75 lenticular and preferably as illustrated, that is to say, the curvilinear double convex cutting edges 11 thereof are intersecting arcs extending from restricted necks at the bases of the blades and producing the pointed outer 80 ends 12, and said cutting edges may be sharpened either by bevelling from one face only, or from both faces of the blade, as may be desired, but preferably in the latter manner as shown in the drawings.

In Figure 5 and 6 of the drawings is shown a modification of the structure in which the same blade elements are employed as in the structure just above described, but in place of the filler or spacing element 4 and the associated handle member 1, a handle 13 is formed of a strip of sheet metal which is rebent or looped back upon itself (see Figure 6), roundly at its outer end, as at 14, and its meeting inner end portions 15 being 95 brought together flatwise and having the blade elements riveted thereon in the same manner as said elements are secured on the filler or spacing element 4 first above described.

Obviously, the meeting end portions 15 of the handle 13 are hardened by any approved tempering or casehardening process so as to preserve the sharpness of the corners 5 thereof as recited in connection with the elements 4 of the structure first hereinabove described.

As shown, the two cutting blades 7 are flared apart slightly towards their pointed ends, preferably, though not necessarily, 10 with curvature as shown.

In the operation of the tool one of the blades 7 is forced endwise into the head of the can close to the periphery thereof, the opposite blade being outside of the can, of course, and as the puncture is made in the head the channel portion 9 of the tool will straddle the marginal bead of the can. Then, by rocking the tool rearward from the direction in which it travels in making the 20 cut, through the leverage afforded by the handle 1 or 13, with the corner 5 of the filler 4 or 15, as the case may be, rearward from the edge 11 of the blade which is doing the cutting, serving as the fulcrum, said cutting edge 11 moves forward and upward and thereby cuts a slit in the head of the can.

During this operation the sharp corner 5 of the tool holds tight with a biting effect on the bead of the can head so as to prevent 30 the tool slipping rearward, yet the tool may be easily slid forward, riding on said corner, on the return reciprocatory stroke of the rocking motion of the handle at the completion of the cutting operation, so that said corner portion 5 may take a new hold on the bead at a point ahead from where it last engaged it, and this reciprocatory actuation of the tool is continued until a circuit of the can head is made. In this way the can head is cut out cleanly and neatly up close 40 to the side wall all around and leaving no jagged inwardly projecting ledge to interfere with the removal of the contents of the can or injure the hand of the user.

45 From the foregoing description and illustrations in the drawings, it is readily apparent that a tool is produced which is simple and inexpensive to manufacture, yet it is highly efficient and possesses many advantages. One particular advantage lies in the fact that the tool may be used either right or left handed and that it may be picked up at random for use in that both blades are identical and double edged, and either blade 55 can be used as the cutter while the other works on the outside of the can and serves as a guide and also works in conjunction with the channel portion 9 to hold the cutting blade close to the wall on the inside of the can. So, too, by having the two cooperating 60 blades in the bifurcated arrangement shown and each with double cutting edges four cutting edges are afforded which, obviously, prolongs the life and usefulness of the tool 65 and makes it practically unnecessary to ever

resharpen the cutting edges, and in any case makes the tool useful for a considerably longer time than if it had only one cutting edge.

The invention comprehends and embraces broadly a bifurcated arrangement of cutting blades, preferably double edged, either blade acting as the cutter and the other as a guide. It is, therefore, not limited to the specific structures shown in the accompanying drawings, as many other modifications in the construction and arrangement of the tool may be made and substituted for those shown without in the least departing from the spirit and scope of the invention as defined by the 70 appended claims.

75 What is claimed is:

1. In a can opener, a substantially rectangular spacing member whose two forward corners afford relatively sharp fulcrum points, and a pair of cooperating like cutting blade members having substantially rectangular base portions of greater width and length so as to extend marginally beyond the side and forward edges of said spacing 80 member and being secured on opposite sides of said spacing member and having lenticular cutting portions proper extending forward from said spacing member and flaring apart from each other towards their ends. 85

90 2. In a can opener, a handle member, a spacing portion at the end thereof, the two forward corners of said spacing portion being substantially right angular and affording opposed relatively sharp fulcrum 95 points, and a pair of like cutting blade members having base portions respectively secured on opposite sides of said spacing portion and projecting marginally beyond the end and side edges of said spacing portion 100 whereby to provide guide channels in correlation to said fulcrum points, said blade members having forwardly extending cutting portions provided with double convex 105 curvilinear cutting edges converging to a 110 point at the outer ends of the blades.

115 3. In a can opener, a substantially rectangular spacing member whose two forward corners afford relatively sharp fulcrum points, a pair of like cutting blade members 120 having substantially rectangular base portions secured cooperatively on opposite sides of said spacing member and having projecting marginal portions affording guides for said fulcrum points along the marginal 125 bead of a can head, said blade members having forwardly extending cutting portions provided with double convex curvilinear cutting edges diverging from a restricted neck at the base and thence converging to a point 130 at the outer end of the blade.

MARSHALL D. GIBSON.
